APPARATUS FOR ORIENTING DRILLING TOOLS

Alphons Gerard Hubert Straatman, The Hague, Netherlands, assignor to Shell Development Company, San Francisco, Calif., a corporation of Delaware

Application May 19, 1937, Serial No. 143,575
In the Netherlands May 22, 1936

4 Claims. (Cl. 33—72)

This invention relates to a method and apparatus for orienting various tools and devices adapted to be lowered into a borehole on a string of tubing or pipe, such as deflecting wedges, whipstocks, knuckle joints, impression blocks, inclinometers, etc.

When orienting in a borehole any drilling tool of the above character, for example, a whipstock, the following procedure is commonly followed:

10 After securely attaching the drilling tool (whipstock) to the first (lowermost) pipe stand, suspended in the derrick, the drilling tool is given a known position in azimuth, which is considered as zero position.

15 The pipe stand and the whipstock are then lowered into the borehole, and the amount of rotation occurring with regard to said zero azimuth position is determined every time another pipe stand is added to the string.

20 For this purpose, it is customary to clamp to the upper portion of every pipe stand being added to the string a special device comprising two members: a stationary member rigidly attached to the pipe, and a rotatable member carrying a

25 sighting device. One of these members is usually provided with a scale, and the other with an index, so that the amount of their rotation with regard to each other can be read on the scale. By aligning the sighting device in a chosen plane

30 of direction, for example, by training it on a distant object as a reference point, the rotatable member is brought into a desired known position, whereafter the scale reading may be taken, and the pipe string lowered in such a manner that the

35 upper portion of the pipe stand is in the position formerly occupied by its lower portion. The amount and direction of the rotation of the pipe and of the drilling tool attached thereto occurring during this process can then be measured

40 by turning the rotatable member until the sighting device is again trained on the reference point. After recording the rotational displacement of the pipe, both members are removed from the pipe and attached to the top of the next pipe section

45 being added to the string and the operation is repeated. In order to minimize the loss of time, two orienting devices, each comprising a stationary and a rotatable member are commonly used in such operations.

50 According to a modification of this method, the pipe string is returned to its original directional position (zero azimuth) after lowering each consecutive pipe section by turning the string until the sighting device is again in alignment with the chosen plane of direction. This method is how-

ever relatively inaccurate and causes considerable delays owing to the difficulty of effecting repeated rotational adjustments of the pipe string.

Both these methods have moreover the disadvantage that a reading has to be taken and recorded after each consecutive pipe stand has been added to the string and lowered into the borehole. This not only causes delay, but, because of the large number of readings required, results in inaccuracies and gives rise to errors, especially 10 in view of the necessity of taking into consideration the algebraic sign of the readings, which denotes clockwise or counter-clockwise rotation of the string.

These drawbacks are eliminated by the use of 15 the method and of the orienting device of the present invention, which permits, first, to measure the separate consecutive rotational displacements of a pipe string without the necessity of recording said measurements, and, second, to obtain automatically the algebraic summation of 20 said separate displacements in order to obtain the total rotational displacement of a pipe string, only a single reading being necessary after the final measurement. This total rotational displacement may be determined with regard to 25 either a known initial position, or with regard to a position to be determined, and the present orientation method may therefore be used either when lowering the pipe string (for example, in 30 placing a whipstock), or when raising the pipe string (for example, in withdrawing an inclinometer or a core orienting device). It is obvious that in such cases changes in the sequence of 35 steps described hereinbelow may be made without departing from the spirit of the invention.

If, in order to save time, more than one orienting device is used, as described below, the readings of the individual instruments will, of course, have to be added up algebraically as the last step 40 of the process.

The present method and orienting device will be better understood from the following description, taken with reference to the attached drawing, wherein:

Fig. 1 is a plan view of the present orienting device, and

Fig. 2, a cross-sectional elevation view of the same device.

Referring to Fig. 1, the drawing shows a clamping member 1 which serves as a support for the measuring device and can be attached to a pipe stand by means of a chain 2. The chain 2 is held by means of a shackle 3 and hook 4 having a tightening screw 5. The clamping member 1 is 55

provided with steel jaws 6 for adjusting the axis of the measuring device in a direction parallel to that of the pipe, and with a handle 7.

The measuring device comprises the following 5 parts, shown in both Fig. 1 and Fig. 2:

(1) A sighting or aligning member 8, such, for example, as a telescope;

(2) A rotatable graduated scale member, such as a plate or ring 10, to which the telescope is 10 connected in fixed relationship by means of a supporting member or fork 9;

(3) A rotatable index member, such as ring 11, concentric with and rotatable with regard to said plate 10, and provided with an index mark which 15 slides along the scale of plate 10 when said plate and the ring 11 rotate with regard to each other.

The scale plate 10 and the index ring 11 can be locked in fixed relationship to each other by tightening the upper clamp screw 12 (shown in 20 Fig. 1), which forces a friction ring 13 against a second friction ring 14, connected to index ring 11, as shown in Fig. 2.

In turn, the index ring 11 is rotatable in the base 15, and can be locked in fixed relationship 25 thereto by tightening a lower clamp screw 16. The base 15 is secured to the tabular part 17 of the clamping member 1 by means of screws 21 and 22.

The telescope 8 comprises an objective 18 forming 30 an image in the front plane of an ocular 19 with engraved cross lines, and can be adjusted by means of a knob 20 at the base of the instrument. This ocular has the advantage that the image can be observed at the normal visual distance 35 without the eye being brought quite near the glass. The telescope is pivotally supported to allow for motion of its axis in a vertical plane up to inclinations of about 30° or more both upwards and downwards.

40 In practicing the method of the present invention the following procedure may be followed when using, for example, two devices of the type described above:

The tool to be oriented is attached to the lower 45 end of the first pipe stand, and is suspended over the borehole in a chosen position. For example, a whipstock or a knuckle joint may be suspended so as to have its plane of symmetry in the direction it should have at the bottom of the bore-hole.

50 The index mark of the index ring 11 of each measuring device is placed opposite the zero mark of the scale 10, and one of the devices is clamped to the top portion of the first pipe section. By loosening the lower clamp screw 16, the index ring 11 is released with regard to the base 15, but remains locked with regard to the scale 10 and to the telescope 8 connected therewith.

60 The telescope 8 is then rotated by means of knob 20 until the line of sight is trained on a distant object, for example, a ranging pole, both the scale 10 and the index ring 11 rotating together with the telescope. After this alignment, the index ring is locked again by tightening the clamp screw 16.

The first pipe section with the device attached thereto is then lowered into the borehole until said device is near the derrick floor. Another pipe stand is then added and the string suspended in 70 the elevator, a certain amount of rotation unavoidably occurring during this operation, and the device rotating together with the string.

75 The upper clamp screw 12 of the orienting device is then loosened, the scale 10 being thereby released with regard to the index ring 11, the

latter, however, remaining locked in relation to the base 15. The telescope 8, together with the scale 10, is then rotated with regard to the index ring 11 by an amount equal and opposite to the rotational displacement of the string during the 5 lowering thereof, until it is again trained on the ranging pole. By tightening again the clamp screw 12 the rotation which has occurred is automatically registered as the displacement between the mark zero on the scale 10 and the index mark 10 on index ring 11, and the new setting of the orienting device may serve as the initial one for the next measurement.

Meanwhile, the operator at the top of the derrick attaches a second orienting device to the 15 top portion of the second stand. The lower clamp screw 16 is released and the telescope trained on the ranging pole, the scale 10 and the index ring 11 again rotating with the telescope. After the clamp screw 16 has been tightened again, the 20 first orienting device below may be removed from the pipe, and the string lowered throughout the length of the second stand. In this manner, the operator on the floor of the derrick manipulates only the upper clamp screw 12, and the operator 25 at the top of the derrick only the lower clamp screw 16, the possibility of errors being thereby minimized.

This cycle of operations is repeated until the 30 whole string has been run in. The total rotational 35 displacement of the tool attached to the lower end of the string is then obtained by taking the algebraic sum of the final readings obtained on each device separately at the end of the whole series 40 of operations. The orientation of the tool at the 45 lower end of the pipe string is then effected as follows:

The orienting device is attached to the last pipe stand, the clamp screw 12 is released, and the zero mark on the scale 10 is brought to register 40 with the index mark on the index ring 11, that is, the device is given its original setting. The clamp screw 16 is then released, and the telescope is rotated together with the scale 10 and the index ring 11 to align the telescope with the ranging pole. The clamp screw 16 is then tightened, the clamp screw 12 released again and the telescope rotated together with the scale until the index mark on the index ring indicates on the scale the total rotational displacement, that is, the 50 algebraical sum of the readings obtained on the two orienting devices after the last pipe stand had been lowered. The clamp screw 12 is then tightened again, and the string of tubing rotated together with the orienting device until the telescope is again trained on the ranging pole, the whipstock or other drilling tool being thereby 55 brought into the desired position.

It is, of course, obvious that a drilling tool can 60 be oriented by the present method while using only one orienting device, although such operation consumes a somewhat longer time.

In such case, the operations are carried out as follows:

The orienting device is attached to the top of 65 the first pipe stand, and the telescope is trained on the ranging pole with the index mark on ring 11 in register with the zero mark on the scale 10. All clamp screws are then tightened and the pipe stand lowered until the orienting device is near 70 the floor of the derrick. The telescope is then trained again on the ranging pole by releasing the clamp screw 12, and rotating the telescope and the scale 10 with regard to the index ring 11. The clamp screw 12 is then tightened, the orienting 75

device removed from the pipe, and hoisted on a cable to the top of the derrick, where it is attached to the top of the second pipe stand. The telescope is then trained on the ranging pole by 5 releasing clamp screw 16, the index ring 11 remaining at the same setting with regard to scale 10 as it was after the sighting operation at the floor of the derrick. The second stand is then lowered into the borehole, and the cycle of operations 10 repeated until the whole string has been run in and the top of the last pipe stand is near the floor of the derrick, the displacement of the index mark on the ring 11 with regard to the zero mark on scale 10 automatically giving the algebraic 15 summation of the rotational displacements of the string occurring as each pipe stand is lowered. The clamp screw 12 is then released, and the telescope rotated together with the scale 10 until the zero mark on the latter registers with the index 20 mark on index ring 11. The clamp screw 12 is then tightened again and the tubing string is rotated together with the orienting device until the telescope is in alignment with the ranging pole, whereby the tool at the end of the pipe string is 25 given its desired position.

It is, of course, understood that the orienting method comprising the steps of returning the pipe string to its original oriented position by rotating it after the addition of each separate pipe 30 stand can equally well be carried out by means of the present device.

I claim as my invention:

1. In apparatus for determining the orientation of a tool supported by a pipe string for longitudinal motion within a borehole, an orienting device adapted to be rigidly clamped to the pipe, comprising a first member rotatable with regard to said device, a second member rotatable with regard to said device and to said first member, 35 and means for positioning said rotatable members in known relationship to a desired orientation

plane, said rotatable members cooperating with each other to indicate the extent and direction of rotation of the pipe during the longitudinal motion of the pipe within a borehole.

2. In apparatus for determining the orientation 5 of a tool supported by a pipe string for longitudinal motion within a borehole, an orienting device adapted to be rigidly clamped to the pipe, comprising a first member rotatable with regard to said device, a second member rotatable with 10 regard to said device and to said first member, means for positioning said rotatable members in known relationship to a desired orientation plane, means for locking said first member with said second member, means for locking said second 15 member with the device, said members cooperating with each other to indicate the extent and direction of rotation of the pipe with regard to the desired orientation plane during the longitudinal motion of the pipe within the borehole. 20

3. An orienting device for determining the orientation of a pipe string within a borehole, comprising a body member adapted to be rigidly clamped to the pipe, a scale member rotatably held by said body member, a sighting member supported in fixed directional relationship in a horizontal plane by said scale member, an index member rotatably held by said body member, said scale member and said index member being rotatable with regard to each other, means for locking 25 the scale member with the index member, means for locking the index member with the body member, said index member cooperating with said scale member to indicate the extent and direction of rotation of the pipe with regard to the desired 30 orientation plane during the longitudinal motion of the pipe within the borehole. 35

4. In the apparatus of claim 3, a sighting device mounted on the scale member for pivotal axial motion in a vertical plane. 40

ALPHONS GERARD HUBERT STRAATMAN.
